VENTILATING CONSTRUCTION

Benjamin S. Reynolds, Madison, Wis., assignor
to Burgess Battery Company, Chicago, Ill., a
corporation of Wisconsin

Application February 18, 1937, Serial No. 126,349

6 Claims.

(CL. 98—4)

This invention relates to ventilating systems, and particularly to air distributing means for the draftless type of ventilation in which an extended air distributor covering substantially the ceiling or one or more walls of the enclosure to be ventilated is employed to divide the air supplied into a multiplicity of fine streams which are directed into the enclosure at all points of the distributor.

10 My invention embodies constructions of the above described type and is particularly adapted to ventilation of vehicles and especially railway passenger cars. Due to the limited space available in the passenger compartment of a railway car, ventilating air inlets are necessarily close to the persons occupying the space, and the problem of supplying sufficient air without drafts is particularly difficult. The extended distributor type of ventilating system offers a solution.

15 Essential factors to be considered in the design of a distributor for such a system include vibration and jolting, odor and dirt accumulation, space limitations, acoustical characteristics and other matters discussed hereinafter as the description of my invention proceeds.

The object of this invention is to provide an extended distributor for vehicle ventilating systems which provides draftless ventilation and a pleasing appearance to the passengers, is rugged in construction, adjustably controls the volume of air passing through any area thereof, does not accumulate odors, and may readily be disassembled for cleaning or adjustment. Other objects and advantages of the invention will become apparent as the description proceeds.

In the drawings:

Fig. 1 is a perspective view, partly in section, showing the interior of a railway passenger car equipped with my air distributor;

40 Fig. 2 is a perspective view of a cross-beam; Fig. 3 is a longitudinal detailed section taken at 3—3 of Fig. 2;

Fig. 4 is a cross-sectional view of the clerestory of a railway car equipped with my air distributor;

45 Fig. 5 is a cross-sectional detailed view of the construction shown in Fig. 4;

Fig. 6 is a longitudinal section of the railway car clerestory shown in Fig. 4, taken at 6—6;

50 Fig. 7 is a detailed section through a cross beam taken at 7—7 in Fig. 1;

Fig. 8 is a transverse sectional view taken at an end of a cross beam;

Fig. 9 is a perspective view of the top of the controlling panel of an air distributing unit;

55 Fig. 10 is a perspective view showing the top of the distributing panel of an air distributing unit; and

Fig. 11 is a perspective view of a modification of the distributing panel shown in Fig. 10.

60 The air distributor which forms the subject

matter of the present invention is in the form of a false ceiling extending between the half-decks of the car roof, as best shown in Figs. 1 and 4. This false ceiling is fabricated from a number of air distributing units designated generally by the numeral 2 and extending across the width of the false ceiling. Before units 2 are arranged in position, the interior of clerestory 4 may be sprayed with a mixture of ground cork and an adhesive 6, such as "Dednox", to prevent rumble and the conduction or radiation of heat and provide a substantially air-tight foundation for the layer of felt or other suitable insulating and/or sound-absorbing material 8 cemented in place between carlines 10 and rafters 12. Preformed sheet metal sections 14, having been previously sprayed with a layer of "Dednox" 13 on their exterior surfaces to damp vibration and provide thermal insulation, are arranged in position and fastened to carlines 10, rafters 12 and stringers 16.

Units 2 are supported by channels 18, which, in turn, are supported by cross beams 20. These cross beams may advantageously be fabricated from sheet metal, a member having a U cross section being provided with holes through which bolts 22 project downwardly. The width of cross beams 20 may be such as to receive the heads of bolts 22 snugly, thus preventing turning of the bolts when nuts 24 are screwed onto them in assembling the distributor. Bolts 22 may be welded in place, if desired, as shown at 26. Metallic strip 28 is spot-welded to the flanges of the cross beam. The purpose of this strip is to add to the strength of the member and prevent the accumulation of dirt in the trough of the beams. Heavy wood or machine screws 30 are used in fastening the cross beams to stringers 16. The flanges of the cross beams and the ends of strip 28 are cut away so that the lower surface of the flanges and stringers 16 are at the same level. Wood fillers or metal boxes 32 may be inserted into cross beams 20 at the ends to prevent collapse when screws 30 draw the beam tightly against stringers 16.

The construction details of unit 2 are best shown in Figs. 4, 5, 9 and 10. Each unit is made up of two members, the upper member being known as the controlling panel, since its function is to control the passage of air from plenum chamber 34 formed in the clerestory as shown in Fig. 1 to the ventilated space below. This control is accomplished by varying the proportion of open area in the controlling panel. The lower panel is known as the distributing member, air passing through controlling panel 36 into a secondary chamber 38, being spread by the distributing panel into large number of fine streams. Distributing panel 40 may conveniently be constructed by spot-welding together abutting

flanges 44 of a series of perforated metal pans 42. The flanges furnish lateral support to the panel which is thereby rendered rigid. A frame 46 is fitted on panel 40, and flange 48 of the frame is 5 spot-welded to the outer flanges of pans 42. An upwardly projecting flange 50 is formed on frame 46, and controlling panel frame 52 is provided with flange 54 of such dimensions that frame 52 will seat snugly on frame 46 when the air distributing unit is assembled. Angle irons 56 may 10 be provided, if desired, to increase the rigidity of the apertured controlling panel 36. These reinforcing members should be positioned on the panel in the direction of air flow in plenum 15 chamber 34 so that the vertical leg will not interfere with the uniformity of distribution of the ventilating air over the area of controlling panel 36 by causing eddy currents. While reinforcing members 56 are preferably used with a sheet 20 metal controlling panel, they may be partially or wholly dispensed with when a pressed board, such as "Masonite" or other fiber board, is used. A self-sustaining sound-absorbing material, such as "Nu-Wood" or "Celotex" may be used, if desired. If one of the latter materials is used, flange 54 of frame 52 may be extended inwardly 25 to provide a support for the controlling panel, and the panel may be bolted to this portion of the frame. Another suitable construction is a 30 unitary controlling panel spot-welded to the flanges of the distributing panel. Obviously, this unit cannot be disassembled for cleaning purposes.

Where the air distributor is subjected to excessive vibration, it may be necessary to provide 35 additional reinforcing to distributing panel 40. The modified distributing panel shown in Fig. 11 is provided with T-bars 58 extending across pans 60 transversely to the flanges of these pans. 40 Each T-bar is rigidly fixed to the pans by riveting or spot-welding angles 62 to the pan flange and to the stem of the T-bar. Frame 64 is identical with frame 46 in Fig. 10.

In assembling the air distributor in the vehicle, cross bears 20 are first fastened in place 45 at proper intervals throughout the length of the car. Each unit, comprising a controlling panel seated upon the frame of a distributing panel, is positioned between a pair of cross beams, the 50 upper surface of the controlling panel frame abutting against the lower surface of the flanges of the cross beams. The unit is held together and in position by moldings 18 tightly drawn upwardly against the distributing panel, as best 55 shown in Fig. 7. The air distributor may readily be disassembled for cleaning by removing each unit and lifting the controlling panel from its seat on the distributing panel frame.

The dimensions of the various parts of the air 60 distributing apparatus must be such that the desired air distribution is obtained. These dimensions may vary for different installations. The plenum chamber must be sufficiently large to 65 carry the ventilating air from the supply duct outlet to all points of the air distributor without moving at too great a velocity over any part thereof. Movement of the air over the controlling panel at relatively high speed causes a horizontal drift of the air as it enters the space 70 to be ventilated. This is an undesirable interference with the uniformity of distribution obtainable with properly designed apparatus.

On the other hand, if the cross-sectional area 75 of the plenum chamber is too great, the time consumed by the air in moving the length of the

chamber is correspondingly excessive. The result is an undesirable heat exchange through the walls of the chamber thereby decreasing the efficacy of the system in maintaining the air in the ventilated enclosure homogeneous. 5

It has been found that if the secondary chamber is made too shallow by spacing the controlling and distributing panels too closely together, the air is not given sufficient opportunity to spread over the distributing member, and the velocity 10 of the air passing through the perforations in the distributing panel in register with the controlling panel openings is considerably greater than that of the air through other portions of this panel. A large number of tests indicate that 15 a secondary chamber $\frac{3}{8}$ inches or greater in depth is satisfactory. 15

The proportion of open area in the distributing panel is greater than that in the controlling panel; consequently, the velocity of the air 20 streams passing through the former is less than that of the streams passing through the latter. Esthetic as well as utilitarian considerations require that the perforations be small and uniformly distributed throughout the area of the 25 distributing panel. This construction spreads the air so that it enters the room and passes therethrough in a blanket-like manner. The proportion of open area in the controlling panel depends upon the volume of air to be allowed 30 to pass through the distributor in the zone at which the particular panel is located. Since the number or size of holes may vary in different distributor installations, or in different zones of the same distributor, a smaller number of large 35 holes may be desirable from the standpoint of manufacturing economy. Small openings may cause whistling. Inasmuch as the arrangement of openings suitable for any particular installation must depend upon the particular conditions 40 there obtaining only general considerations can be set out here and a specific example given. 40

In one railway car ventilating system installation, the air distributor consists of a false ceiling, made up of eighteen air distributing units 45 36×66 inches. Ventilating air is supplied to the plenum chamber at one end of the car at the rate of about 2300 cubic feet per minute and the vitiated air is exhausted from the passenger space at floor level at the same end of the car. 50 The plenum chamber is approximately $19\frac{1}{2}$ inches deep and the controlling panel measures 60 inches in width. The air distributor which is 54 feet long is divided into three zones as 55 follows:

Zone 1, nearest the supply of ventilating air, is made up of five units, the controlling panels are 0.533 per cent open having 2 three-quarter inch holes per square foot;

Zone 2, intermediate, is made up of 7 units, 60 the controlling panels are 2.14 percent open having 6.4 three-quarter inch holes per square foot;

Zone 3, in the end of the distributor remote from zone 1, is made up of 6 units, the controlling panels are 3.24 percent open having 9.6 three-quarter inch holes per square foot. 65

All distributing panels are uniform, being 10 percent open and having 15 three thirty-second inch holes per square inch. These dimensions 70 are not critical and the number and size of holes may be somewhat varied. The holes may be of any shape and arranged in any desired patterns.

In this particular ventilating construction 75

fresh air enters the passenger space uniformly throughout the area of each zone. Since air introduced into the remote end of the car must travel the length of the car before it is exhausted or re-conditioned, its temperature is subject to change as it travels through the car due to heat transfer through the walls of the car or radiation from the sun and heat given off by the passengers. This air is available to the passengers for breathing for a greater length of time and, consequently, is subject to greater contamination. In order to maintain the air in all parts of the car homogeneous, the controlling panels of the zones remote from the intake and exhaust end of the car are provided with a larger proportion of open area than those near the supply and, as shown above, the ventilating air thereby being supplied to the car in quantities which increase roughly with the distance of the point in the car supplied from the source of supply. This zoning may also be accomplished by plugging a portion of the holes in the controlling panel, all panels being uniformly apertured.

Acoustical observations have shown that the noise level within the passenger car is materially reduced by the action of the double panel air distributor, probably due to a Helmholtz resonator effect in secondary chamber 38 and plenum chamber 34 together with the dissipation of the sound waves passing from one medium to another of different temperature and density. If further acoustical correction is desired, the upper and side walls of the plenum chamber may be of sound-absorbing construction. This may be accomplished by selecting an insulating material which is capable of serving the double function of heat insulator and sound-absorber, such as hair or jute felt, "Balsam wool", mineral wool, cork, metal foil, etc. If desired, this material may be faced with a sound-transparent, air-impervious material to protect the absorber-insulator and prevent the passage of air into the material and attendant accumulation of dirt and odors. Metal foil, paper, or "Cellophane" is suitable for this purpose. If a metal foil absorber-insulator is used, such a facing is unnecessary. Or, a perforated sheet metal facing may be used as shown in Norris Patent No. 1,726,500 dated August 27, 1929. This perforated facing may be backed by an air-impervious, sound-transparent film cemented to the metal for the purpose above set forth.

The specific example described above illustrates my invention and is sufficient to enable one skilled in the art to practice the same.

Although I have illustrated the invention as used in a railway car of wooden construction, only minor changes would be required in a steel car installation. Machine screws and tapped holes may be used as supporting means. Further, the invention may be adapted to many uses other than passenger car ventilation, the particular construction described being useful as an air distributor for the ventilation of other vehicles and other ventilating systems.

I claim:

1. In a ventilating system for a vehicle, air-distributing apparatus comprising a chamber extending longitudinally superjacent the vehicle interior, a plurality of removable air dis-

tributing units arranged in edge-to-edge relation to form an apertured partition between said chamber and said vehicle interior, each of said units comprising a controlling panel and a distributing panel, said distributing panel comprising a perforated panel-like member and a frame interlocking with the distributing panel and having a flange extending away from said distributing panel, said controlling panel comprising an apertured panel-like member and a frame adapted to seat in the frame of said distributing panel whereby to interlock said controlling panel against lateral movement relatively to said distributing panel and to space said controlling panel from said distributing panel.

2. In a ventilating system for a vehicle, air-distributing apparatus comprising a chamber extending longitudinally superjacent the car interior, a plurality of removable air distributing units arranged in edge-to-edge relation to form an apertured partition between said chamber and said vehicle interior, each of said units comprising a controlling panel and a distributing panel, said distributing panel comprising a plurality of perforated pans in side-by-side relation and a frame interlocking with the bounding flanges of the pan assembly and having a flange extending away from said pan assembly, said controlling panel comprising an apertured panel-like member and a frame adapted to seat in the frame of said distributing panel, whereby to interlock said controlling panel against lateral movement relatively to said distributing panel and to space said controlling panel from said distributing panel.

3. The construction of claim 1 and including reinforcing members on said distributing panel.

4. The construction of claim 1 and including reinforcing members on said controlling panel.

5. An air-distributing unit for a ventilating system comprising, in combination, a controlling panel and a distributing panel, said distributing panel comprising a perforated panel-like member and a frame interlocking with the distributing panel and having a flange extending away from said distributing panel, said controlling panel comprising an apertured panel-like member and a frame adapted to seat in the frame of said distributing panel whereby to interlock said controlling panel against lateral movement relatively to said distributing panel and to space said controlling panel from said distributing panel.

6. In an air-distributing apparatus for a ventilating system, a space to be ventilated, a plenum chamber, a plurality of removable air-distributing units arranged in edge-to-edge relation to form an apertured partition between said chamber and said space, each of said units being a demountable assembly comprising a controlling panel and a distributing panel, said distributing panel comprising a perforated panel-like member and a frame interlocking with the distributing panel and having a flange extending away from said distributing panel, said controlling panel comprising an apertured panel-like member and a frame adapted to seat in the frame of said distributing panel, whereby to interlock said controlling panel against lateral movement relatively to said distributing panel and to space said controlling panel from said distributing panel.

BENJAMIN S. REYNOLDS.
